US00D758771S

(12) **United States Design Patent**
Austin, III et al.

(10) **Patent No.:** **US D758,771 S**
(b4) **Date of Patent:** **** Jun. 14, 2016**

(54) **SHOWER DOOR DISPLAY**(71) Applicant: **LIBERTY HARDWARE MFG. CORP.**, Winston-Salem, NC (US)(72) Inventors: **James Allen Austin, III**, High Point, NC (US); **Matthew Klein**, Apex, NC (US); **Patrick Boehnen**, Summerfield, NC (US); **Laura Hawkins**, Madison, NC (US)(73) Assignee: **LIBERTY HARDWARE MFG. CORP.**, Winston-Salem, NC (US)(***) Term: **14 Years**(21) Appl. No.: **29/480,762**(22) Filed: **Jan. 29, 2014**(51) LOC (10) Cl. **06-06**

(52) U.S. Cl.

(57) **CLAIM**

The ornamental design for a shower door display, as shown and described.

DESCRIPTION

FIG. 1 is a perspective view of a shower door display; FIG. 2 is a front side elevation view of the shower door display of FIG. 1; and,

FIG. 3 is a right side elevation view of the shower door display of FIG. 1.

The broken lines are for illustrative purposes only and form no part of the claimed design.
